UNITED STATES PATENT OFFICE.

THOMAS V. WARNER, OF WAUKEGAN, ILLINOIS.

PUMP.

SPECIFICATION forming part of Letters Patent No. 253,247, dated February 7, 1882.

Application filed May 31, 1881. (No model.)

To all whom it may concern:

Be it known that I, THOMAS V. WARNER, of Waukegan, in the county of Lake and State of Illinois, have invented certain Improvements in Pumps, of which the following is a specification.

This invention relates to the construction of well and cistern pumps; and it consists in the novel combination and manner of construction of the several parts, as hereinafter fully set forth.

The accompanying drawings, which form a part of this specification, show at Figure 1 a plan view of the pumping-cylinders with the top-protecting plate removed; at Fig. 2, an end view, partly in section, of the same parts; at Fig. 3, a horizontal section of the same upon the line *x x*, Fig. 2; at Fig. 4, an elevation of the handles and spout at the upper end of the pump or main tube; at Fig. 5, an exterior view of one of the cylinders; and at Fig. 6, a cross-section of the same upon the line *y y*, Fig. 5; and at Fig. 7, a section of the main tube.

Like letters indicate like parts in all the figures where they appear.

A A are two parallel cylinders, placed horizontally at the bottom of the well or cistern. Each of these cylinders has a central inlet-port, *a*, and a central filling-piece, *a'*, located directly under the inlet, and dividing the cylinder into two parts, and I call them "double cylinders," because they are thus divided. The filling-piece leaves a square opening into each part of the cylinder from the inlet-port, (shown in dotted lines at Fig. 6,) and such opening is filled or covered by a hinged or flap valve, *a''*. Two reciprocating pistons or plungers, B B', are inserted in each of the cylinders A, one plunger at each end and upon either side of the inlet-port.

Extending from each half or part of the cylinder to the corresponding half of the other cylinder is a cross-passage, C, each cross-passage containing a ball-valve, *c'*, whereby it may be alternately opened and closed at each end.

In practice I place between the two cylinders a block, D, which supports them, and cut these passages in said block; but if the block is not used, tubes may be specially provided for the purpose. An upright tube, E, is stepped

in this block, or otherwise supported, and openings *e* into it from each of the cross-passages are provided.

The plungers are reciprocated by a pinion, F, encircling the tube E, and racks G, meshing with said pinion and rigidly connected at each end with the outer end of one of the plungers by a depending piece, *g*, and screws *g'*. The upper portion of the cylinder is cut away at each end, as at *g''*, to give the necessary room for reciprocation. The pinion F is secured upon the foot of the up-flow pipe H, which is placed over the tube E sleeve-fashion, so that the latter acts as a pivot upon which the tube H may be turned. At the top, or above ground, the tube H is provided with one or more laterally-projecting arms, *h*, whereby it may be swung or semi-rotated, and a spout, *h'*, which may be loose thereon, and held by some stationary device, so it will remain still during the semi-rotation of the main tube. A bearing will naturally be provided for the tube near the point where power is applied to it, if it is so long as to need such.

A ball, I, is inserted in the main tube to serve as a valve, with the top of tube E for its seat. It prevents the water which may be above it in the tube from flowing back. It is confined to a limited upward movement by the cross-pin *i*. By the use of a valve at this point the pump is always made ready for instant service, and water may be drawn with the first strokes of the handles.

A covering-plate, J, is preferably employed to prevent injury to the working parts by the falling thereon of material from above, and to keep the gears clear. A bottom piece, K, is also used to strengthen and support the parts.

With the pump thus constructed the operation is as follows: With each motion of the handles, tube, and pinion all the plungers are reciprocated, one plunger, B, in each cylinder toward its inlet-port and the other, B', in the same cylinder away from said port. In this movement the plungers which move toward their ports cause a pressure upon the water which has gained access to the interior of the cylinders between them and the valves *a''*, which hang in and close the inlet-openings into their parts or ends of the cylinders, and such pressure instantly closes said valves and pre-

vents the escape of the water through that channel. The water, being thus cut off from escape through the port-holes, immediately seeks another outlet, and this it finds in the cross-passages C, driving the balls c, as it enters said passages, to the farther end thereof, so they will close the openings into the other cylinders. The water is now compelled to enter the center tube, E, and through it and its connecting-tube H it reaches the outlet. In the other halves of the cylinder—viz., those in which the plungers are moved away from the inlet—the outside pressure of water opens the valves a^2 and rushes in and fills any vacant space in those parts of the cylinder due to the retreat of the plungers. When the movement of the semi-rotating parts is reversed the operation just described as taking place in the parts of the cylinder holding the plunger B and their connecting passages is duplicated in the parts holding the plungers B' and their connections, and the operation of filling as-

cribed to the latter (cylinders B') is duplicated in former, (cylinders B,) and so on. The two sets of plungers alternate with each other with 25 each reversal of the movement of the actuating devices.

The pumping devices are secured in the well by stakes driven into the earth, or in any other appropriate way. The plungers should displace as little water as possible, and hence I hollow out the inner ends at b, as shown.

I claim—

The combination, with the plungers and the up-flow tube, of the pinion and racks, whereby 35 the semi-rotation of the tube is caused to reciprocate the plungers and the tube to serve a double purpose, substantially as specified.

THOMAS V. WARNER.
